UNITED STATES PATENT OFFICE.

DANIEL W. MILLSAPS, OF WASHINGTON, DISTRICT OF COLUMBIA.

DOOR.

1,273,520.

Specification of Letters Patent. Patented July 23, 1918.

Application filed November 7, 1917. Serial No. 200,835.

To all whom it may concern:

Be it known that I, DANIEL W. MILLSAPS, a citizen of the United States, residing at Washington, in the District of Columbia, 5 have invented new and useful Improvements in Doors, of which the following is a specification.

This invention relates to a door of the type wherein provision is made for ventilating the room or the like, in the entrance to 10 which the door is mounted.

The primary object of the invention is to provide a door of this character wherein the top and bottom rails of the door are 15 spaced from the ends of the stiles to provide the door with ventilating openings which are normally closed by panels hingedly connected with the above-mentioned rails to permit the panels to be moved to a 20 position wherein the ventilating openings will be unobstructed thereby.

Another object of the invention is to provide a door wherein the panels may be yieldably, yet firmly held in position to obstruct 25 the ventilating openings by springs, the connection of which with the door and the panels is such, that when the panels have been moved to a position wherein the ventilating openings are unobstructed thereby, the 30 spring will not exert an influence upon the panels tending to restore the panels to their normal position.

A further object of the invention is to 35 so recess the rails and panels which serve as closure members for the ventilating openings that the door has formed therein pockets for the reception of the springs which firmly yet yieldably maintain the panels in 40 position to obstruct the ventilating openings in the door.

With these and other objects in view, the 45 invention resides in the novel combination and arrangement of parts, which will be hereinafter described and particularly pointed out in the claim.

The preferred embodiment of the invention has been illustrated in the accompanying drawings, although no restriction is necessarily made to the precise details of construction therein shown, as changes, alterations, and modifications within the scope of 50 the claim may be resorted to when desired.

In the drawings:—

Figure 1 is a view in front elevation of a 55 door constructed in accordance with the invention.

Fig. 2 is a similar view looking at the opposite side of the door.

Fig. 3 is a view in side elevation of the door and showing the panels moved to a 60 position in which the ventilating openings in the door are unobstructed thereby.

Fig. 4 is a detail sectional view through the top rail and panel associated therewith and showing the panel firmly yet yieldably 65 held in position to close the ventilating openings adjacent the top of the door.

Fig. 5 is a view similar to Fig. 4 wherein the panel which acts as a closure member for the ventilating openings adjacent the top 70 of the door is shown in lowered position.

Like characters of reference denote corresponding parts throughout the several views in the drawings.

Referring now to the drawings in detail 75 the letter A designates a door constructed in accordance with the invention and which in this instance has been shown of the panel type although I desire it to be understood that other types of doors may be constructed 80 in accordance with the invention if desired.

The door A as constructed in accordance with the invention has the top rail 5 and the bottom rail 6 spaced from the ends of the stiles 7 to provide the door with ventilating 85 openings 8 adjacent the top and bottom thereof. The rails 5 and 6 and stiles 7 are rabbeted, as at 9 to permit screens 10 to be arranged within the opening A and secured to the stiles to prevent insects from entering 90 a room in the entrance to which the door A is mounted.

The ventilating openings 8 are adapted to be closed by panels 11 each of which is hingedly connected with one of the rails of 95 the door A and has formed in one end thereof a pair of recesses 12 which open out at one end through the said end of the panel and one side thereof.

When the panels 11 are in position to obstruct the ventilating openings 8 the recesses 12 in each panel register with the recesses 13 in the rail to which the panel is attached, the recesses 13 in the panels correspond in shape to the recesses 12 so that each recess 13 opens out at one end through an end of the rail and one side thereof. The recesses 12 and 13 form within the door A pockets in each of which is arranged under tension a coiled contractile spring 14 and these 110 springs are terminally connected with securing elements 15. The elements 15 are

passed through the recesses in the rails and panels and also through eyes at the terminals of the spring.

- Connected with each of the panels 11 is an operating rod 16 by means of which the panels may be swung to a position upon the door wherein the panels will not obstruct the openings 8 and to insure the panel which is connected with the rail 6 remaining in such position, the montant of the door A has mounted thereon a keeper 17 with which may be engaged a hook 18 at one end of the rod 16 on the panel which is connected with the rail 6.
- When the panel 11 is in position to obstruct the ventilating opening adjacent the bottom of the door A the operating rod 16 thereon may be held in an out of the way position by engaging the hook on the rod with another keeper 19.

In order that the door A may fit tightly within the frame and that the panels may be swung to a position in which the ventilating openings are unobstructed I provide each panel with a curved end 20, the curved end 20 on the upper panel 11 being adapted to contact with the lintel of the door frame while the curved end 20 on the panel at the lower end of the door is adapted to overlie the door sill.

Through the above described manner of arranging and connecting the springs 14 with the rails and panels 11 on the door it will be seen with references to Fig. 4 in the drawing that when the panels are in position to obstruct the openings 8 the springs 14 are under tension and firmly yet yieldably hold the panels in the above mentioned position.

When the panels have been moved to open position as shown in Fig. 5 in the drawing it

will be observed with reference to this figure that by so arranging the recesses 12 and 13 that they open out through one side of the rails and panels the springs are caused to assume a shape corresponding to that of an inverted U, so that the springs lie to one side of the hinge connection of the panels with the rails and with the tension of the springs relaxed, thus, insuring the panels remaining in open position.

From the foregoing description taken in connection with the accompanying drawings it is apparent that a door has been provided which though simple in construction and inexpensive of manufacture is highly efficient for the purpose set forth.

Having thus described the invention, what is claimed as new, is:

A door having its top and bottom rails spaced from the ends of the stiles to provide openings at the top and bottom of the door, said rails having recesses therein opening out through one side edge of the rails, panels in said openings hingedly connected with the rails and having recesses in one side edge thereof coacting with the recesses in the rails in providing pockets extending above and below the hinge connection of the panels with the rails, and springs under tension in said pockets connected with the panels and rails, said recesses opening out at one end through one side of the panels and rails contiguous to the side edge of the panels and rails in which the recesses are formed, whereby when said panels are in lowered position said springs are disposed to one side of the hinge connection of the panels with the rails with the tension of said springs relaxed.

In testimony whereof I affix my signature.

DANIEL W. MILLSAPS.
